Patented July 5, 1921.

FIG. 3.

FIG. 2.

FIG. 1.

Inventor

Nicholas Power
By his Attorney

W.B. Morton

UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

LAMP-HOUSE FOR MOVING-PICTURE APPARATUS.

1,383,754.

Specification of Letters Patent. Patented July 5, 1921.

Application filed October 12, 1915, Serial No. 55,408. Renewed December 7, 1920. Serial No. 429,036.

To all whom it may concern:

Be it known that I, NICHOLAS POWER, a citizen of the United States, and a resident of Brooklyn, in the county of Kings and 5 State of New York, have invented new and useful Improvements in Lamp-Houses for Moving-Picture Apparatus, of which the following is a specification.

This invention relates to lamp houses for 0 arc lamps of the character used for the projection of motion pictures, and has for its object to provide a lamp house in which a high powered arc can be used with perfect 15 safety and so designed that no part of the lamp house becomes sufficiently heated to burn the operator, or ignite the film in case of accidental contact therewith.

A further object of the invention is to provide a lamp house having attached condensers for focusing the light on the picture strip which is so constructed that the condensers are protected from intense heat and also from rapid changes of temperature when the arc is extinguished which cause the 25 condensers to break.

A further object of the invention is to provide a lamp house with the above features presenting an attractive appearance and which may be constructed substantially 30 throughout of stamped sheet metal and consequently of low cost.

Further objects of the invention will appear from the specification taken in connection with the accompanying drawings 35 wherein I have illustrated a preferred embodiment of my invention, it being understood of course that the invention is not limited to the details of construction shown and described except in so far as recited 40 in the appended claims.

Figure 1 is a side elevation of my improved lamp house;

Fig. 2 is a vertical longitudinal section through the lamp house shown in Fig. 1; 45 and

Fig. 3 is a partial transverse section showing the door construction.

Referring now to the drawings in which like parts are indicated by the same characters throughout the several views, 1 indicates the metal base board of the lamp house 50 provided with the usual concave rollers 2 for supporting the lamp house on the transverse rods 3 of its stand. The upper por-

tion of the lamp house is composed principally of sheet metal and comprises a rear wall 4 having suitable holes for the projection of the adjusting screws 5 by means of which the position of the arc can be adjusted relative to its supporting post 6 without opening the doors 7 of the lamp house. The lamp house preferably is provided with doors on each side which constitute the major portion of the side faces. Above and below the doors the side walls 8 are provided with a series of ventilating holes 9 extending laterally across the entire width of the side wall and opening into channels formed by the pieces 10 attached to the inner face of the walls and open at the ends so as to direct the air drawn into the ventilating holes by the heat of the lamp, upward against the end walls of the lamp house.

The front wall 11 of the lamp house is composed of sheet metal except for the reinforcing piece 12 for supporting the bracket 13 in which the condenser lenses 14 are mounted in position with their optical centers in alinement with the crater of the arc. The lower portion of the front wall 11 projects beyond the edge of the base 1 to provide a ventilating opening 15 at the bottom of the front wall. The air received through the opening 15 is deflected backwardly between the arc and the condensers 85 by the inclined portion 16 of the front wall which joins the lower edge of the piece 12. Above the condenser bracket the front wall is bowed outwardly as shown at 17 to provide a ventilating opening 18 for the admission of air between the sheet metal wall and the front face of the piece 12.

An opening 20 is provided in the top wall of the lamp house near the rear edge for the egress of the air drawn in through the above 95 described openings so that a continuous current of air through the lamp house is maintained when the light is on. The top wall is protected from the heat of the lamp by means of a partition 21 which extends from the rear wall to a point near the front of the lamp house whereby a lateral current of air is maintained across the under face of the top wall serving to prevent the top wall becoming excessively heated. The opening 20 100 is preferably provided with a short chimney 22 for augmenting the draft through the lamp house and for directing the heated air 105

upwardly where it will not cause discomfort to the operator.

The doors of the lamp house are preferably double walled as indicated in Fig. 3 and are bowed outwardly as shown to increase the distance between their inner surfaces and the arc. The outer wall 23 is provided on its bottom inclined portion with a series of ventilator holes 24 for admitting air to the space between the two walls, which air passes upwardly through a series of similar holes 25 in the inclined wall at the top of the door, thus insuring free circulation of air which keeps the outer wall of the door from becoming overheated.

With the development of the motion picture art, and the increasing popularity of motion pictures as an entertainment, the theaters have increased in size, necessitating a much greater distance of projection, and the demand for larger and more brilliant pictures has become such that arc lights of very high power, some using carbons of an inch and a half in diameter, are necessary to secure the desired results. Arc lights of this character generate a large amount of heat and if inclosed in a lamp house of the ordinary construction without special provisions for cooling, the walls of the lamp house will, after a brief period of operation, become so hot as to be liable to injure the operator, and also to ignite the film or any other inflammable material with which they may come in contact.

In my improved lamp house, however, the arrangement of the various ventilating passages is such that a sufficient current of air in circulation to absorb the heat of the arc is maintained over the entire inner surface of the outside walls, leaving no part to become heated to a dangerous temperature. The double walled doors constitute substantially the entire side walls, except the parts immediately above and below the doors in which the ventilating openings are formed. The channel pieces into which the side ventilating holes open direct the air to the end walls of the lamp house, and serve to keep them cool with the aid of the air received through the openings provided in the rear wall for the adjusting screws and the special ventilating passages in the front wall. The partition plate at the top of the lamp house protects the top wall from the direct rays of the arc, and also causes the outgoing air to pass across the entire length of the lamp house before reaching the egress opening. The chamber formed by this plate also adds to the flue length, and as the plate is exposed to the greatest heat of the lamp, it adds greatly to the force of the draft, insuring sufficient circulation at all times.

Another important feature of my improved lamp house is the arrangement of the ventilating passages in the front wall. The

arrangement is provided to protect the condenser lens from the heat of the arc and also to prevent their too rapid cooling which is one of the chief causes of breakage. The large amount of air admitted through these openings affords a sufficient absorbing medium to carry off the greater portion of the sensible heat of the arc, but the lenses are also heated to a large extent by the radiant heat of the arc, from which they cannot of course be protected. The danger of breakage from this heat is not so great while the arc is lighted as when it is extinguished, for the lamp house, being hot, will maintain a circulation of air after the arc is extinguished, and should this cold air be drawn in large volume over the lenses after the radiant heat of the arc is cut off, they will be cooled so rapidly as to break. For this reason the large ventilating opening is provided above the lenses. When the arc is out, the air currents are created chiefly by the hotter metal at the top of the lamp house, and hence practically all the air will be taken in at the upper opening, allowing the lenses to cool slowly.

What I claim is:—

1. A lamp house for projecting lamps, consisting of a housing, doors forming the greater portion of its side walls, said doors embodying air circulating means, said walls below said doors being provided with a ventilating opening for the ingress of air, and means for directing the air received through said opening toward the end walls of the housing, said housing having an egress opening at the top thereof.

2. A lamp house for projecting lamps, consisting of a housing, doors forming the greater portion of its side walls, said doors embodying air circulating means, said walls below said doors being provided with a ventilating opening for the ingress of air, said housing having a top wall provided with an opening near one end for the egress of air and an inner top wall spaced below the outer wall and permitting the passage of air only at the end opposite the said egress passage.

3. A lamp house for projecting lamps, consisting of a housing having a lens mounted in its front wall, said housing having openings for the ingress of air below said lens and in its front wall above said lens, and a closure for the top of said lamp house having an opening for the egress of air adjacent the front wall substantially above said openings, said housing being so designed that the air entering through said ingress openings passes vertically upward to said egress opening and across the rear face of the front wall of the housing.

4. A lamp house for projecting lamps consisting of a housing inclosing the arc, lenses supported in one vertical wall of said

housing, said housing having an upper horizontal wall or roof, an air egress opening in said roof at a point remote from said lens supporting wall, a baffle plate supported below said opening and forming an air space between said plate and said roof, an opening in said air space adjacent said lens carrying wall, and air ingress openings above and below said lens positioned to direct the air admitted by said openings across the inside

face of the lens-supporting wall to the opening in the air chamber.

Signed at New York city, in the county of New York and State of New York, this 15th day of September, 1915.

NICHOLAS POWER.

Witnesses:

J. F. SKERRETT,
ARTHUR J. LANG.

It is hereby certified that in Letters Patent No. 1,383,754, granted July 5, 1921, upon the application of Nicholas Power, of Brooklyn, New York, for an improvement in "Lamp-Houses for Moving-Picture Apparatus," an error appears in the printed specification requiring correction as follows: Page 2, lines 122-123, claim 3, strike out the words "substantially above said openings"; and that the said Letters Patent should be read with this correction therein that the same may conform to the record of the case in the Patent Office.

Signed and sealed this 30th day of August, A. D., 1921.

[SEAL.]

KARL FENNING,

Acting Commissioner of Patents.
